Application March 2, 1956, Serial No. 40,433

Term of patent 14 years

(Cl. D3—13)

FIG. 1

Except to the extent shown in Fig. 2, the opposite side to that shown in Fig. 1 is plain and unornamented.

I claim:

The ornamental design for a hat, substantially as shown and described.
